UNITED STATES PATENT OFFICE

2,229,731

CASH REGISTER AND THE LIKE MACHINE

Michael Jacob Fort, Copenhagen, Vanlose, Denmark, assignor to The National Cash Register Company, Dayton, Ohio, a corporation of Maryland

Application March 8, 1939, Serial No. 260,647
In Germany March 9, 1938

10 Claims. (Cl. 101—93)

The invention relates to cash registers and the like machines and more particularly to a printing mechanism for such machines which is adapted to selectively effect a variable number of imprints on various record materials by a printing hammer coacting with a plurality of groups of type wheels, including a group of amount type wheels. In such printing mechanisms, column selection has to be provided for, since certain kinds of entries require imprints of the data and amounts to be entered in separate columns on the said record materials.

Heretofore in column selection mechanisms, either the amount type wheels—see, for example, U. S. A. Letters Patent No. 1,311,884 to Fuller—or the data type wheels and the printing table have been shiftably arranged. Such arrangements result in a complicated structure of the printing mechanism due to the shifting and controlling device necessary for at least one of the groups of type wheels.

Thus the main object of the present invention is to enable column selection with all the groups of type wheels arranged stationary.

Another object of the invention is to provide for simultaneous and successive actuation of printing hammers coacting with the various groups of type wheels.

Another object of the invention is to arrange means for properly shifting the printing table between successive printing hammer strokes.

Another object of the invention is to adapt the printing table shifting means for varying the extent of table shift.

Still another object of the invention is to arrange means for controlling the table movements in accordance with a transaction performed.

With these and incidental objects in view the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a front view of the printing mechanism and the special key bank showing also the various key detents,

Fig. 2 is a top plan view of the printing mechanism and the means for shifting the printing table,

Fig. 3 is a side view of the special key bank and of the differential mechanism cooperating therewith,

Fig. 4 is a side view of the special key bank and the machine release mechanism controlled thereby,

Fig. 5 is a side view of the special key bank partly in section taken on the line II—II of Fig. 1,

Fig. 6 is a side view of the printing hammer actuating mechanism,

Fig. 7 is a front view of the table shifting mechanism in one position,

Fig. 8 shows in a front view the table shifting mechanism in another position,

Figs. 9 and 10 show in side elevations details of the table shifting actuating mechanism,

Fig. 11 is a front view of the printing table and the line selecting mechanism,

Fig. 12 is a top plan view of the type wheel set arrangement,

Fig. 13 is a side view of the consecutive number device and its actuating device,

Figs. 14 and 15 show forms of record materials imprinted by the machine.

General description

The invention is herein shown embodied in a cash register provided in a well known manner with a printing mechanism in which the printing hammers are actuated a plurality of times during a machine operation in order to make the same impression on several record materials which are inserted into the machine. Such machines provided with the novel arrangement are installed in a cashier's window of a savings bank, or the like establishment, especially in a small branch office of it, where, due to the small number of customers and the low amounts handled, an installation of a posting or accounting machine may not be economical.

In such a case, record materials to be imprinted upon comprise an insertable deposit slip, a ledger card and a pass book. The deposit slip, of the kind shown in Fig. 15, is filled in and duly signed by the customer and handed to the cashier together with the pass book. After having secured the customer's ledger card, of the usual type as shown in Fig. 14, the cashier first inserts the deposit slip, then the ledger card and then the pass book, to have the same data such as the date, consecutive number, ledger number and amount of the transaction, i. e. of the deposit or withdrawal as well as a symbol for signifying the amount, W for withdrawal and D for deposit, printed thereon by the machine. Such small machines are usually not provided with an add and subtract or balance totalizer. Therefore

when such a machine is used for the purposes above outlined, the new balance to be obtained from an old balance of an account and a deposit or withdrawal is not calculated by the machine, 5 but by the cashier, who has to set up the new balance on the amount key board and operate the machine in order to have the new balance printed on all the three record materials.

With such accounting it is essential that the forms of ledger cards used in the branches and in the central office be the same. This is the more important, as the receipts have to be sent to the central office, to have the customer's main ledger cards properly made out. Only the duplicates are kept in the branch offices. In order to obtain identical imprints in the central office, by the highly efficient accounting machines, and the small machines installed in the branch offices, the latter are provided with the novel column selecting device according to the invention which is fully described hereinafter.

25 The machine in which the invention is shown embodied may be either electrically or hand operated. Such machine is provided with the usual ledger number keys and amount key banks (both not shown), the amount keys being used to enter amounts into the machine, which are, as the case may be, either deposits or withdrawals, and credit or debit balances. The key board further 30 comprises a bank of transaction keys 11, 12 and 13, of which the key 11 serves for deposit entries, the key 12 for withdrawal ones and the two keys 13 for credit and debit balances respectively. These transaction keys control, in addition, the 35 selection of totalizers proper (not shown) into which the amounts set up on the amount key banks are entered, and also the machine release mechanism, which is provided with a well known automatic stopping device for interrupting machine 40 operation before completing its cycle. Such an automatic stopping and releasing mechanism is shown and described in U. S. A. Letters Patents Nos. 1,658,993 and 1,991,560 to Kömmiling and No. 1,761,572 to Kropff, to which reference may be 45 had for a more detailed description.

In addition, these keys control the adjustment of a type wheel to print symbols (W, D, NC, ND) corresponding to transaction keys depressed.

50 The printing mechanism, as shown and described, comprises, in addition to the beforementioned type wheel and a group of amount type wheels, at least one group of type wheels for printing the date, another for the consecutive number, and still another for the ledger number.

55 A printing hammer coacts with the date, consecutive number, and ledger number type wheels, and another printing hammer coacts with the amount group of type wheels and with the symbol type wheel. In accordance with the transaction keys
60 depressed at the time, said hammers are actuated singly, simultaneously or successively, in the manner hereinafter described.

Special keys

65 The special keys 11, 12 and 13 (Figs. 1, 3, and 4), which function as transaction and machine release keys, are slidably mounted in a key frame 24 carried by rods 25 and 26 supported at their ends in the side frames of the machine. The keys 70 11, 12 and 13 carry laterally projecting studs 16, 17 and 18, 19 respectively, which, when said keys are depressed, coact with the inclined slots 20, 21, 22 and 23 in a detent 15 and rock the latter upwardly against the action of a spring 14. The detent 75 15 is supported at both ends by a bifurcated

portion thereof embracing a stud 27 and 28, respectively, carried by the frame 24, while at its upper end it is pivotally connected to a zero stop pawl 29 pivoted on a stud 116 in the frame 24. Thus whenever the detent 15 is rocked upward 5 in the manner just described it will rock the zero stop pawl 29 clockwise (Fig. 4) to an ineffective position.

Another detent 110 (Figs. 1 and 4) of an old and well known type, which cooperates, as will be specified below, with the release and stop mechanism, retains the keys 11, 12 and 13 in their depressed positions until near the end of the operation of the machine, when said detent is caused to release the keys to the action of coiled springs (not shown) which return them to their normal undepressed positions. When this occurs the spring 14 then returns the detent 15 downwardly to its home position and, at the same time, moves the pawl 29 counter-clockwise to its 20 normal effective position.

There are arranged in this key bank four other detents 151 to 154 and also a detent 240, the function of which will be described later in connection with the printing mechanism. 25

Differential mechanism

The differential mechanism associated with the special keys 11, 12 and 13 adjusts means for controlling operation of the machine, as will be hereinafter described. Such a differential mechanism is well known in the art and specified in the U. S. A. Letters Patent No. 2,139,719 to Breitling et al. 30

This differential mechanism includes a differentially movable actuator 30 (Figs. 3, 4 and 5) which, through a latch 31 pivoted thereon, is driven first counter-clockwise (Figs. 3 and 5) and then clockwise during each operation of the machine by a driving segment 32 fast on a shaft 33 journaled at its ends in the side frames of the machine. A foot 34 on the latch 31 is constantly held in cooperative relation with the periphery of the segment 32 by a spring 35. The driving segment 32 receives a constant excursion of movement, first in a counter-clockwise direction and then in a clockwise direction, during each operation of the machine by means hereinafter described. 40 45 46

As the segment 32 is thus rocked counter-clockwise the foot 34 of the latch 31 will, near the end of such movement, be rocked into engagement with a shoulder 36 on said segment by the spring 35. Then as the segment 32 is returned clockwise to its home position it will, through the engagement of the shoulder 36 with the foot 34, carry the latch 31 and the actuator 30 along with it until a resilient pawl 37 on said latch strikes either the zero stop pawl 29 or the stem of a depressed key 11, 12 or 13. When this occurs the pawl 37 is thereby rocked counter-clockwise and causes the latch 31 to be rocked likewise. This disengages the foot 34 from the shoulder 36 and, at the same time, engages a locking projection 38 on said latch with one of a series of notches 39 in a locking plate 40 attached to the frame 24. The actuator 30 is thus locked in its moved position, while the segment 32 continues its counterclockwise movement until it reaches its home position.

Secured to a main drive shaft 50, suitably journalled at its end in the machine side frames, is a cam 51 (Figs. 1 and 3) having a cam groove 66 coaxing with a roller 67 on an arm 69 pivotally mounted on a rod 68 suitably supported

in the machine. The shaft 50 and cam 51 receive one complete rotation in a counter-clockwise direction (Fig. 3) upon each operation of the machine. When this occurs, the configuration 5 of the groove 66 is such that the cam 51 will rock the arm 69 first clockwise and then counter-clockwise during each operation of the machine. The arm 69 has formed integral therewith a toothed rack 70 meshing with a segment 71 secured to the shaft 33. It will thus be apparent that when the cam 51 rocks the arm 69 in the manner just described, the latter will, in turn, rock the gear 71, shaft 33 and driving segment 32 first counter-clockwise and then clockwise.

The differentially movable actuator 30 is returned to its home position during the next succeeding operation of the machine by the surface 43 on the segment 32 coating with the stud 44 20 on said actuator when the segment is rocked clockwise.

Machine stoppage and release device

For starting machine operation either the deposit key 11 or the withdrawal key 12 or one of the two balance keys 13 (Figs. 1 and 4) has to be depressed. Upon depression of one of these three keys, its pin 16, 17, 18 or 19 respectively, coacts with an inclined slot 111, 112, 113, 114, 30 respectively, associated therewith in a detent 110 rockably arranged on the studs 27 and 28 and rocks this detent 110 downwardly. Thereat, a shoulder 118 of the detent 110 frees a projection 120 arranged on an arm 119 pivoted on a 35 stud 116 and connected by means of a rod 121 to the one arm 124 of a bell crank lever mounted on a machine release shaft 122. The other arm 125 of the lever embraces by its bifurcated end a stud 126 of a clutch control lever arm 128 rockably arranged on a shaft 127. The control lever arm 128, the end of which cooperates with a projection 132 of a clutch disc 131, is connected by a sleeve to a clutch member 129 loaded by a strong spring 130. The disc 131 rotatably arranged on the machine main shaft 50 is connected to a gear 134 engaging a pinion 136, mounted on a shaft 135. When the machine is operated by means of an electric motor the clutch disc 131 forms a part of the driven member of a clutch 45 mechanism on the machine main shaft 50.

On the arm 119 a spring actuated pawl 138 is rotatably arranged which is forced by its spring 139 in the path of the shoulder 118 of the detent 110.

If now one of the transaction keys 11, 12 or 13 is depressed, and the detent 110 is moved downwardly, the shoulder 118 pushes the pawl 138 aside against the action of its spring 139. As simultaneously the shoulder 118 leaves the path of the projection 120, the spring 130 becomes effective and rotates the arm 119 clockwise. Thereat, the projection 120 is moved above the shoulder 118 and prevents restoration of the detent 110 under the action of its spring 140 and also of the depressed transaction key. Further, the clutch control lever arm 128 is disengaged from the projection 132 of the clutch disc 131 and, by the spring 130, the arm 129 is rocked into the path of pins 142, 142' and 142'' on a 50 gear 141 mounted on the main shaft 50 and meshing with a gear 143 rigidly connected to the pinion 136. The ratio of the gearings is such that the disc 131 is rotating through two full revolutions, when the gear 141, and thus the main shaft 50, is making one revolution.

Since now the clutch members 128 and 129 are out of engagement with the disc 131, the machine is released for operation. After the gear 141 and thereby the shaft 50 has been rotated through 180°, the pin 142 engages the arm 129 5 and rotates it and the arm 128 counter-clockwise. Thereby the arm 128 is moved into the path of the projection 132 of the disc 131 having revolved in the meantime nearly through 360° and arrests it. At the same time, the arm 119 is restored by the rod 121 to its rest position and therewith also the detent 110 by its spring 140, thus releasing the depressed key 11, 12 or 13.

In this manner the machine is locked at all 15 events after half a revolution of the main shaft, and this locking takes place after the first operation of the printing mechanism. The operator now inserts the second record material to be imprinted into the machine, and presses once 20 more the same transaction key 11, 12 or 13 to release the machine. This second revolution extends, however, only to 90° of the main shaft revolution. After this part-revolution, the pin 142' engages the arm 129 and forces the clutch 25 member 128 into the path of the projection 132' of the locking disc 131. Likewise, in the manner already described, the depressed transaction key is released again. Now, the third record material is inserted into the machine, the same 30 transaction key is depressed, and the machine is operated the third time, until the pin 142'' finally stops the machine.

In order to force the machine operator to depress for each part-revolution the same transaction key 11, 12 or 13 with which he started machine operation, in the transaction key bank four more detents 151 to 154 are provided (Figs. 1 and 5), each one having an inclined surface and a plurality of locking surfaces, which co- 40 operate with the pins 16', 17', 18', 19' of the transaction keys 11, 12, and both the balance keys 13 respectively. By depressing one of the keys, say 11, the pertinent detent 151 is lifted, whereby the other keys 11 and 13 are locked. In 45 the same manner the keys 11 and 13 are locked by means of the detent 152 upon depressing the key 12. The upper end of each of the four detents 151 to 154 has a hook projection 155 to 50 158 which, when the detent moves upward, engages from behind the projection 160 of an arm 161 of a bell crank rotatably mounted on a shaft 165, the other arm 162 of which is spring actuated and has a working surface 164 cooperating with a square pin 166 of a pitman 163. The pitman 163 is guided by the shaft 135 projecting into an elongated slot 168 of it and actuated by a cam 169 fast on the main shaft 50. The cam 169 cooperates with a pin 170 of the pitman 163. The bifurcated end of the pitman 163 embraces 55 the shaft 50.

This arrangement for making it necessary to depress the same key for a number of successive operations is well known in the art as may be taken from U. S. A. Letters Patent No. 2,116,779 60 65 to Breitling to which reference may be had for a more detailed description.

Printing mechanism

In the printing mechanism there are arranged 70 one set of type wheels 200 for the date printing, one set 201 for printing the consecutive number, one set 202 for the ledger number and one type wheel set 203 for the amounts and a type wheel 204 for the symbols (Figs. 1, 6, 12 and 13). 75

The type wheel sets 202 to 204, mounted on the shaft 192, are differentiated by gearings 193 to 199 actuated by the associated differentials (Figs. 3 and 12), whereas the type wheels 201 for the consecutive number are adjusted by a device which will be described later. The date type wheels 200 are set by hand by means of the knobs 191. The arrangement is well known in the art wherefore no detailed description is deemed necessary.

An impression hammer 206, freely mounted on a shaft 207 (Figs. 2 and 6), is common to and cooperates with the type wheel sets 200 to 202. The hammer 206 contacts by its stud 208, due to gravity, an actuating lever 209. The lever 209, pivotally mounted on the shaft 207, has a roller 210 coating, under the action of a strong spring 211, with the periphery of a cam member 212 secured to a shaft 214 driven by the main shaft 50 through a train of gears 215, 216, 217, 218 and 219 (Figs. 1, 2 and 6). Thus rotation of the shaft 214 is stopped whenever the main shaft 50 is arrested after a part-revolution of 180°, 90° and 90° as explained above. The cam member 212 comprises three lobes 220, 221, 222 (Fig. 6) by one of which the impression hammer 206 is actuated during one of the three partial operations, to print on the record material at the time inserted, the date, the consecutive number and the ledger number.

A separate impression hammer 226 (Figs. 1, 2 and 6) is provided for the amount type wheel set 203 and symbol type wheel 204, which hammer is driven by a lever 228 actuated by a cam member 231. The cam member 231 also comprises three lobes 232, 233, 234, the first one 232 actuating the hammer 226 at the same time as the first lobe 220 of the cam 212 does the hammer 206, while the two remaining lobes 233, 234 of the cam member 231, being staggered on the shaft 214, are rendered effective at a later instant than the corresponding lobes 221, 222 of the cam member 212. Due to this arrangement of the hammer driving cam lobes, the two impression hammers 206 and 226 operate at the same time during the first partial operation, whereas during the second and third partial operations, the wide impression hammer 206 operates first and, some time later, the amount impression hammer 226 operates. In that way after an impression of the date, consecutive and ledger number is taken, the record material inserted can be shifted to the desired amount column wherein the amount is to be printed (compare Figs. 14 and 15). The column to be imprinted among the three columns provided is determined by the kind of transaction, that is, whether the amount is a deposit, a withdrawal, or a balance. Consequently column selection is controlled by one of the transaction keys 11, 12, 13 (Figs. 1 and 3) as described below.

For column selection the printing table has to be shifted in the interval between the various hammer strokes. The mode of shifting is determined by the transaction key depressed. For that purpose the before mentioned key detent 240 (Figs. 1 and 3) is provided in the transaction key bank. The detent 240 is normally held in its upper position by a spring 241. The detent 240 is provided with slots 242, 243, 244, 245, the form of which determines the kind of cooperating with the key pins 16', 17', 18', 19', in such a way that the detent 240 is not moved at all by the depression of the deposit key 11, 75 while it is moved by one step upon the depression

of the withdrawal key 12 and by two steps upon the depression of each of the two balance keys 13.

The detent 240 is connected by a crank lever 246 and a link 247 to an arm 248 pinned to a shaft 250 (Fig. 3). A pin 249 of the arm projects in an elongated slot 249a of the link 247. The object of this arrangement will be to permit restoration of the detent 240 and to permit a transaction key to be depressed after a part 10 machine operation without changing the adjustment of said shaft 250 effected by the said transaction key originally depressed. The other end of this shaft has fixed thereto an arm 251 the stud 252 of which engages a grooved sleeve 253 (Figs. 2 and 7). The sleeve 253 is shiftably but unrotatably mounted on a shaft 255 and is normally held in its left hand end position by a spring 256 (Fig. 7). The sleeve 253 is integral with an arm 257 having a roller 258 engaging, 20 when the sleeve is in its normal (left) position, a groove 259 of a cam disc 260 (Fig. 9). The cam disc 260 is pinned to a shaft 261 (Figs. 7 and 8) rotating through one full revolution for each full cycle of a machine operation when 25 actuated by the shaft 214 through a train of gears 262, 263, 264, 265, 266 (Figs. 2 and 7). But as mentioned before, the shaft 261, due to its actuation by the main shaft 50 or rather by the shaft 214 connected to the latter, is also 30 stopped when the main shaft is stopped and released respectively and thus any actuation of the cam disc 260 is controlled by the transaction key depressed and thus by the detent 240.

To the shaft 255 also an arm 267 (Figs. 1, 2 35 and 6) is secured to which a link 268 is pivoted. The link 268 is fixed at its other end to the printing table 270 arranged shiftably in the cross direction on rollers 271 (Fig. 7). A spring 272 holds normally the printing table 270 in its rest 40 position (Figs. 1 and 2). Thus the printing table 270 is moved whenever the shaft 255 and the arm 267 are rocked.

The rest or left hand end position of the sleeve 253 is maintained whenever the deposit 45 key 11 is depressed, since the detent is not moved during this machine operation. According to the configuration of the cam groove race of disc 260 (Fig. 9) the arms 257 and 267 are not moved during the first partial operation, thus maintain- 50 ing the printing table 270 in the initial position.

During the second partial operation, the printing table 270 first remains in its rest position but is then shifted by the first raise of the groove 55 259 of the cam disc 260 acting upon the roller 258 and thus actuating the arms 257 and 267 by one step corresponding to the width of a column towards the left, so that the print of the amount takes place in the second column provided for deposits in the ledger card (Fig. 14). Then the 60 printing table is returned into its initial position by means of the cam disc 260.

During the third partial operation the same operative conditions prevail as in the second one, that is to say, after the date and consecutive 65 number are printed by the impression hammer 206, the printing table 270 is shifted by one column towards the left, so that the print of the amount is effected, this time by the hammer 226 in the second amount column of the third record 70 material, the pass book. Thereafter the printing table is restored into the rest position.

When the withdrawal key 12 is depressed, the detent 240 is moved downwardly one step (Fig. 3) and the lever 251 shifts the sleeve 253 and the 75

arm 257 one step towards the right (Figs. 7 and 8) to disengage the roller 258 from the groove 259 of the cam disc 260. In this position of the sleeve 253 neither the arm 257 nor the arm 261 is actuated and thus the printing table 270 is not moved at all during all the three partial operations.

In order to prevent in this position of sleeve 253 any movement of the table 270 by hand, a finger 275 rigidly arranged on the sleeve 253 contacts a fixed stop 276 (Figs. 1 and 8). All the amounts are therefore printed in the first amount column of the record materials (Figs. 14 and 15).

Upon depressing one of the balance keys 13, 15 the detent 240 is lowered two steps (Fig. 3) and the shaft 250 is rocked so far that the lever 251 shifts the sleeve 253 and its arm 257 by two steps into its right hand end position (Fig. 7), whereby another roller 273 of the arm 257 engages the 20 periphery of a cam disc 274 pinned to the shaft 261 (Figs. 1, 2, 7 and 10).

At the beginning of this operation, the arms 257 and 261 are rocked counter-clockwise (Fig. 1) thus shifting the printing table by two steps, that is, by two columns towards the left. Owing to the configuration of the cam disc 274, the printing table is maintained in such a position during all three partial operations that the three strokes of the printing hammer 226 cause the 30 print of the amount set up, in the right hand or balance column (Figs. 14 and 15).

The printing hammer 206 is not to be actuated during the registration of any balance, as this item is printed on the same line as the previous 35 deposit or withdrawal (Figs. 14 and 15) and, as said before, all the data such as date, consecutive number and ledger number have been already printed together with the amount of the deposit or withdrawal. For disabling the hammer 206 40 the printing table 270 is provided with a block 278 (Figs. 1, 2 and 6) which when the table has been moved by two steps engages the one arm of a crank lever 279 and rocks said lever in such a way that its other arm locks the hammer 206. 45 When the hammer driving lever 209 is actuated, the hammer 206 is prevented from following the lever 209 when released, so that no hammer stroke is initiated and no print is effected at all.

The transaction keys 11 to 13 which determine 50 the extent of shifting of the printing table are machine operation release keys as already mentioned and have to be released after each partial operation. This is done by the rod 121 of the stopping and releasing mechanism after 55 each partial operation. Restoration of the detent 240 into its rest position does not affect the adjustment of shaft 250 due to the slot and pin connection between link 247 and arm 248 (Fig. 3). In order to force, however, completion of 60 any transaction started, the shaft 250 is latched in its initial adjustment during the whole machine operation by a locking segment 281 secured to the shaft 250 and provided with three notches (Fig. 2) each associated with one of the transaction keys 11, 12 or 13. A locking pawl 282 65 pivoted on a stud 286 is adapted to enter one of said notches under the action of a roller 284 arranged on said pawl 282 which roller engages, by the pressure of a spring 283, the periphery 70 of a cam disc 285 pinned to the shaft 214.

Upon depression of one of the transaction keys 11, 12, 13, the shaft 250, the segment 281 and the arms 257 and 261 are rocked counter-clockwise (Figs. 1 and 3) to an extent determined by the 75 respective transaction key depressed, and the

shaft 250 is held adjusted during the whole cycle of machine operation by means of the locking pawl 282, engaging one of the notches of the segment 281 during all the three succeeding partial operations actuating it due to the configuration of the cam disc 285.

Consecutive number device

The consecutive number device is advanced by one step for each transaction performed. As 10 entering a deposit or withdrawal and printing the balances are a part of a single transaction, the advancing movement of the consecutive number type wheels is suppressed in balance entering operations. The consecutive number type 15 wheels 201 are advanced by a pawl 291 (Figs. 12 and 13), mounted on a yoke 292 actuated by a cam disc 294 by means of a lever 293. The cam disc 294 is connected, by means of gears 295, 296, 297 with a shaft 298 rotatably and shiftably 20 mounted in the machine frame. By means of a clutch 299—300, the shaft 298 is coupled with a driving shaft 301, thus causing the advance movement of the consecutive number type wheels 201. When the printing table 270 is shifted into the left hand end position, an arm 302a of a yoke 302 secured to the table 270 contacts a collar 303 mounted on the shaft 298 and shifts the latter so far that the clutch 299—300 is disengaged, thus disconnecting the shaft 298 from the 25 driving shaft 301. Upon this movement, a stud 304 engages a notch 305 of a fixed wall 306 and the shaft 298 is locked against any rotation. During this shift the pinion 297 pinned to the shaft 298 remains in mesh with the wide pinion 296, although the driving member is separated from the driven member of the clutch and thus the consecutive number device is locked. When, after the print of the balance, the printing table 30 270 is restored into its rest position under the 35 action of its spring 272, an arm 302b of the yoke 302 contacts the collar 303 and returns the shaft 298 into its initial position in which it is connected by the clutch 299—300 to its driving shaft 301. 40

Line selection

The printing table 270 is provided with a guiding frame 310 (Figs. 1, 2 and 11) which is mounted shiftably thereon, in order to insert and set 50 the record material to the line desired. Underneath the frame 310 a rail 311 is fixed, provided with a series of holes 312 each corresponding to one of the lines. Below this rail 311, a bar 313 is fixed having mounted thereon a locking lever 314 which, under the action of a spring 318, engages, by its pointed stud 315, a bevelled groove 316 provided on the end of the shaft 214. This lever has also a pin 317 arranged to enter into a hole 312 of the rail 311. The groove 316 of the 60 shaft 214 lies in the path of the stud 315 when the shaft 214 is in the home position (Fig. 11). Thereat, the stud 315 is positioned in the groove 316 and the lever 314 is lowered to such an extent that the pin 317 is disengaged from the holes 312 65 of the rail 311, thus allowing the guiding frame 310 to be moved by hand to select the desired line. Upon rotation of the shaft 214 at the start of the machine operation the stud 315 leaves the groove 316. The lever 314 is raised thereby and 70 the pin 317 enters the hole 312 representing the line selected. Therefore the printing table 270 is locked in the same line position until the shaft 214 has ended its full revolution, that is, after all the three partial operations are completed. 75

Operation

To register a deposit, the transaction key 11 is depressed. The detent 240 together with the sleeve 253 and the arms 257 and 267 remain in their normal positions. The roller 258 of the arm 257 is kept in engagement with the cam groove 259 (Figs. 7 and 9) by which the printing table 270 is not moved during the first partial operation, so that upon simultaneous actuation of both hammers 206 and 226 on the receipt (Fig. 15)—which comprises only two amount columns—besides the date, consecutive number and ledger number, the amount and the symbol D are printed in the first amount column. After removal of the receipt the operator inserts the ledger card.

To release the second and the third partial operations, the same deposit key 11 has to be depressed. When by inadvertence the operator tries to depress another transaction key 12 or 13, this is prevented by detent 151 associated with key 11, which locks all the other keys, and also by shaft 250 which, at this time, is locked in the initial position by the pawl 282 engaging the first notch of segment 281. Thus upon depressing the deposit key 11 the second time the second partial operation is initiated. At the beginning of the operation, the printing table 270 remains in its initial position until the impression hammer 206 has been actuated to print in the corresponding columns of the ledger card (Fig. 14) the date, the consecutive number and the ledger number. Then the printing table 270 is moved by one step towards the left by the cam disc 260 (Figs. 1, 7 and 9) and the printing hammer 226 is actuated. Thereby the amount is printed in the second amount column, the deposit column. Thereupon the table 270 is restored into its initial position.

During the third partial operation, the same working sequence is maintained, except that the imprint is made upon the pass book which has been inserted previously to depressing the key 11 the third time.

To register a withdrawal, the transaction key 12 is depressed, thus lowering the detent 240 by one step and rocking the shaft 250 through a certain angle counterclockwise (Fig. 3). The sleeve 253 as well as the arms 257 and 267 are moved to the middle position (Fig. 8) in which neither the roller 258 nor the roller 273 engages its cam disc 260 or 274 respectively. When the machine is released for operation, the printing table 270 remains stationary and as, in this case, the shaft 250 is locked in its second position during all three partial operations, the print of the amount set up takes place in the first amount column, that is, the withdrawal column (Fig. 14) in each partial operation of this transaction. The release of the second and third partial operations can be accomplished by the withdrawal key 12 only, because by the detent 152, pertinent to this key, all the others are locked, and by the pawl 282 engaging the second notch of segment 281, shaft 250 is secured against any movement.

The new balance of an account, obtained from the old balance and a deposit or a withdrawal, is computed by the cashier and set up on the machine, as normally these types of machines have no add and subtract totalizer. The release of such an operation is obtained by the lower key 13, if the balance is positive, and by the upper key 13, if the balance is negative. In both cases, the detent 240 is lowered by two steps and the shaft 250 rotated through a corresponding angle.

The sleeve 253 is moved thereby to its right hand

end position in which the roller 273 engages the cam disc 274 (Fig. 10). At the beginning of the operation the cam disc 274 shifts the printing table 270 two steps corresponding to the extent of two columns towards the left (Fig. 1). Thereby the block 278 disables by the lever 279 the printing hammer 206, whereas by the yoke 302 the clutch 299—300 is rendered ineffective to prevent any advance of the consecutive number type wheels 201. Therefore, in each of the three partial operations of this transaction, only the hammer 226 is actuated to effect the imprint of the balance in the right hand amount column of each record material successively inserted. Towards the end of the third partial operation, the printing table 270 is restored into its initial position.

In the embodiment of the invention shown and described, the shifting of the printing table is effected automatically by the machine operation. It is of course also possible to obtain an automatic shifting movement of the printing table, during the machine operation from the withdrawal position into the deposit position, while owing to a locking condition between the printing table 270 and the transaction keys 12 25 or 13, the printing table would have to be positioned by hand, at the beginning of the operation, in the withdrawal column or in the balance column, before one of the transaction keys 12 or 13 may be depressed.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class specified the combination of a plurality of stationary type wheels comprising data and amount type wheels; a printing hammer coacting with said data type wheels; a printing hammer coacting with said amount type wheels; means for actuating said hammers in a predetermined sequence; a printing table movable for columnar printing; and means operable during a single machine operation to move said printing table from a certain columnar position to a different columnar position, after an actuation of one of said printing hammers but prior to the actuation of the other printing hammer, whereby data is printed in two different columns during a single machine operation.

2. In a machine of the class specified the combination of a plurality of stationary type wheel sets comprising data type wheel sets and an amount type wheel set; a printing hammer coacting with said data type wheel sets for printing in one column of record material; a printing hammer coacting with the amount type wheel set for printing in another column of said record material; actuating means for said hammers to coact with the respective type wheel sets in a predetermined sequence during a single machine operation; a printing table; means for shifting said printing table for column selection; and means for actuating said shifting means in the interval between the actuations of the above named printing hammers.

3. In a machine of the class specified the combination of a plurality of stationary type wheel sets comprising data type wheel sets and an amount type wheel set for printing in different columns on record material; a printing hammer

coacting with said data type wheel sets; a printing hammer coacting with the amount type wheel set; actuating means for said hammers to coact with the respective type wheel sets in a predetermined sequence a plurality of times during a single machine operation; a printing table adapted to be set to various columnar positions; means for shifting said printing table to select columns for printing; and means for actuating said shifting means to move the table after actuation of the one of said printing hammers into one of said columnar positions.

4. In a machine of the class specified, the combination of a main drive shaft for the machine, operated one complete rotation for each machine operation; an automatic stopping device cooperating with the machine drive shaft for interrupting the rotation of the drive shaft a plurality of times before completing its rotation; a plurality of stationary type wheel sets comprising data type wheel sets and a single amount type wheel set; a printing hammer coacting with the data type wheel sets; a printing hammer coacting with said amount type wheel set; a cam member operatively connected to the drive shaft for actuating the data type wheel hammer during the part rotations of the machine drive shaft; a cam member operatively connected to the drive shaft and formed differently from the first named cam member for actuating said amount type wheel hammer at another time, during the various part rotations of the machine drive shaft, than the first named hammer; a shiftable printing table; and means connected with the drive shaft to move said printing table between actuation of said printing hammers for printing in different columns from the amount type wheel sets.

5. In a machine of the class specified, the combination of a machine drive shaft, operated one complete rotation for each machine operation; an automatic stopping device cooperating with the machine drive shaft for interrupting the machine operation a plurality of times before the shaft completes its rotation; a plurality of stationary type wheel sets; printing hammers adapted to coact with said type wheel sets in a predetermined sequence during each partial rotation of the drive shaft to print in a different column on record material during each partial rotation of the drive shaft; a shiftable printing table for carrying the record material; means for shifting the printing table to select a column on the record material; and means for selectively connecting said shifting means with the printing table to vary the movement of said table for columnar selection.

6. In a machine of the class specified the combination of a machine drive shaft, operated one complete rotation for each machine operation; an automatic stopping device cooperating with the machine drive shaft for interrupting the rotation of the drive shaft a plurality of times before the shaft completes its rotation; a plurality of stationary type wheel sets; a plurality of printing hammers; means actuated by the main drive shaft to cause the printing hammers to coact with said type wheel sets in a predetermined sequence during each partial rotation of the machine drive shaft; manipulative devices; a printing table for carrying record materials; and means connected to the drive shaft for shifting said printing table under control of the manipulative devices to variably shift the table for columnar selection between the strokes of printing hammers during each partial rotation of the machine drive shaft.

7. In a machine of the class specified the combination of a machine drive shaft operable one complete rotation for each machine operation; an automatic stopping device cooperating with the machine drive shaft for interrupting operation of the drive shaft a plurality of times before the drive shaft completes its rotation; a plurality of stationary type wheel sets; a plurality of printing hammers; means connected to the drive shaft and adapted to coact with said type wheel sets during each partial rotation of the machine drive shaft in a predetermined sequence; manipulative devices; a locking device for one of said printing hammers, actuated by a certain of said manipulative devices when operated; a printing table for carrying record materials; and means connected with the drive shaft for shifting the printing table relatively to the type sets, under control of the manipulative devices to vary the movement of the said printing table for printing in various columns.

8. In a machine of the class specified the combination of a machine drive shaft operable one complete rotation for each machine operation; an automatic stopping device cooperating with the machine drive shaft for interrupting the operation of the drive shaft a plurality of times before completing its rotation; a plurality of stationary type wheel sets comprised of data type wheel sets and an amount type wheel set; a common printing hammer for all the data type wheel sets; a printing hammer for said amount type wheel set; a cam member for actuating the data printing hammer and another cam member for actuating the amount printing hammer, said cam members operated through connections to the drive shaft and adapted to variably actuate both of said printing hammers during the various partial rotations of machine drive shaft operation; a machine release mechanism cooperating with said stopping device; a bank of transaction keys adapted to be depressed in a predetermined sequence in two subsequent machine operations and connected to said machine release device for actuating it; a printing table having various columnar positions each one of said transaction keys selecting a different columnar position; cam discs for shifting the printing table into its columnar positions; connections between the cam discs and the drive shaft; and a control member adapted to be actuated by the transaction keys for selecting the cam disc which is to be operatively connected to the printing table.

9. In a machine of the class specified the combination of an automatic stopping device cooperating with the machine drive for interrupting machine operation a plurality of times before completing its cycle; a machine release mechanism cooperating therewith; a plurality of stationary data type wheel sets; a single stationary amount type wheel set; a printing hammer common to all the data type wheel sets and coacting therewith; a printing hammer coacting with the amount type wheel set; a cam member for actuating the data printing hammer and another cam member for actuating the amount printing hammer, said cam members being differently structured to actuate the hammers in a predetermined sequence during the part-cycles of the interrupted machine operation; various kinds of transaction keys adapted to be selectively depressed in two subsequent machine operations and operatively connected with the release mechanism to release the machine for all part-cycles of its operation; a printing table having various set positions ap-

pertaining to one kind of said transaction keys each; a disabling member for said data printing hammer actuated by the printing in a certain of its set positions; cam discs for shifting the printing table into its set positions between the strokes of both said printing hammers when subsequently actuated; and a control member adapted when actuated by the one kind of transaction keys, to select and operatively connect one of said cam discs with the printing table and when actuated by another kind of transaction keys, to operatively connect another disc with the printing table to vary its movement, and to remain in its initial position with a third kind of the transaction keys depressed.

10. In a machine of the class specified the combination of an automatic stopping device cooperating with the machine drive for interrupting machine operation a plurality of times before completing its cycle; a machine release mechanism cooperating therewith; a plurality of stationary data type wheel sets including a consecutive number type wheel set, moved by one step in each machine operation; a single stationary amount type wheel set; a printing hammer common to all the data type wheel sets and coacting therewith; a printing hammer coacting with the amount type wheel set; a cam member for actuating the data printing hammer and another

cam member for actuating the amount printing hammer, said cam members being differently structured to actuate the hammers in a predetermined sequence during the part-cycles of the interrupted machine operation; various kinds of transaction keys adapted to be selectively depressed in two subsequent machine operations and operatively connected with the release mechanism to release the machine for all part-cycles of its operation; a printing table having various set positions appertaining to one kind of said transaction keys each; a disabling member for said data printing hammer actuated by the printing table in a certain of its set positions; cam discs for shifting the printing table into its set positions between the strokes of both said printing hammers when subsequently actuated; a control member adapted when actuated by the one kind of transaction keys to select and operatively connect one of said cam discs with the printing table and when actuated by another kind of transaction keys, to operatively connect another disc with the printing table to vary its movement, and to remain in its initial position with a third kind of the transaction keys depressed; and a consecutive number disabling mechanism actuated by said third kind of transaction keys when depressed.

MICHAEL JACOB FORT.
